STOP MOTION FOR CORE WRAPPING MACHINES

Armand Bès, Paris, France, assignor to William Oliver Larmuth, Alpraham, near Tarporley, Cheshire, England

Application May 21, 1932, Serial No. 612,806
In France July 31, 1931

2 Claims. (Cl. 117—45)

The present invention has for object a mechanical arrangement which automatically stops a machine using a bobbin of textile or analogous material (paper in rolls, rubber in thread and so on) as soon as the thread which is being used unravels or breaks or again as soon as the bobbin is full.

In the new arrangement which is shown by way of example in the accompanying drawing 10 which represents the table of a core wrapping machine in elevation at Fig. 1 and in plan at Fig. 2 a general support 1 receives a central spindle 2 held in appropriate bearings. This spindle is integral with a plate 3 which supports 15 a bobbin 4 which contains the textile material and a hook for guiding marked 5. On the other side of the plate a member serves to maintain the equilibrium in order to obtain a regular rotation. The extremity of the spindle consists 20 of an enlarged portion 2' on which is formed a screw thread with a long pitch and rounded edges. On this part is mounted with suitable play, a ring 6 carrying two arms 7 and 8 of equal weight and well balanced statically and 25 dynamically for the speeds under consideration. One of the extremities of these arms protrudes into the interior of the bore of the ring 6 and engages very freely in the screw thread referred to here above in such a manner that if this 30 ring 6 is threaded on the enlarged portion of the central spindle by engaging with the internal nipple in the screw thread, the ring 6 in falling by its own weight is compelled to make a rotary movement in the direction of the helicoidal groove.

On the other hand a lever 9 drawn towards the exterior by a spring 10 is disposed on a stationary part of the support 1 and can turn to a certain extent about an axis 11. The upper extremity of the lever 9 is engaged through a plate 12, likewise secured on the general support, this plate being slotted and terminated in a notch which, when the end of the lever 9 is engaged therein, prevents the same from being returned by the spring (Fig. 2).

Forward of this lever is disposed a shaft 13 preferably carrying a screw with deep rectangular screw threads 14 disposed opposite the lever 50 9 which is terminated by a heel piece 9' the thickness of which is less than the depth of the screw threads. This lever, on the other hand, is of suitable length so that its upper end shall be approximately at the middle of the two extreme positions which the ring 6 can take up in

the diameter over which the arms 7 and 8 can sweep.

This screw is pinned fast on the shaft 13 which is driven by means of a key 13' which is very 5 slideable, by a pulley 15 which itself is driven by the intermediary of a belt by another pulley 15' integral with a main shaft which drives by suitable means the central shaft 2, and which carries on the other hand any stop mechanism, for example a stationary pulley 16 and a loose pulley 10 16'. Over these pulleys can pass a belt 17 which connects with a driving drum (not shown on the drawing) in such a manner that it passes between two discs which are fast on the shaft 13, and can act on the belt in the manner of 15 a belt fork for disengagement. This shaft 13 is presumed to be supported by smooth very soft bearings which can slide.

Before starting up this machine the lever 9 is engaged in the stop of the groove, the thread 20 which comes from the bobbin which is presumed to be suitably braked is passed around the guide hook and attached to the core which passes into the central hole and which is brought step by step upwardly in known manner and according 25 as the winding takes place. By attaching this thread to the core, the ring 6 has been brought into the position indicated by the full lines (Fig. 1) and the thread coming from the bobbin passed through the forks of the arm 7 in such a manner 30 that the tension of the thread opposes the natural tendency of the ring to screw down on the screw thread and return to the position indicated in dotted lines. If now the machine is set in rotation 35 it is evident that, if the tension of the thread is sufficient, the ring and its arms will be driven thereby very readily because of the good equilibrium of this part and its slight resistance to the air. The plane of the arms 7 and 8 therefore passes above the extremity of the 40 lever 9.

It is presumed by way of example, that the plate seen from above turns in the direction of the hands of a watch and that the screw thread 45 extended on the extremity of the central shaft 13 is to the left. It is evident that in this case if the machine turns and the unravelled or broken thread occurs the ring 6 which is free on the axis is no longer driven; it tends to screw down and consequently to descend and in this movement the arms strike the lever 9 which through the shock is driven out of the stop or notch and, drawn by the spring 10, slides in the groove. The heel piece 9' of the lever which is rigid and 50 fixed engages in the threads of the screw which 55

is formed with the rectangular screw threads and marked 13 and which continuously turns through the action of the grooved pulleys 15 and 15' and which consequently force the shaft 13 into a longitudinal displacement movement which varies with the direction of the thread of the screw. It is here presumed that the direction is such that the shaft whilst turning is drawn according to the direction of the arrow indicating the top of Fig. 2. In this displacement the shaft 13 slides through the pulley 15 which remains in line with the pulley 15' and drives the discs 17' which releases the belt by causing it to slide over the loose pulley 16'. At this moment the machine stops, the lever 9 is in an inclined position towards the exterior which indicates that it has operated and the heel piece 9' which is engaged in the groove at the bottom of the thread of the screw opposes any starting up. It is therefore necessary to re-attach the thread by lifting the ring 6 to its running position and return the lever 9 to its position of rest. At this moment it is possible to re-engage by displacing the shaft 13 towards the bottom of Fig. 2.

The operation previously given is given by way of illustration but it is obvious that an equally good result would be obtained with a rotation of the plate in a direction contrary to that indicated or by replacing the pulleys 15 and 15' by gear wheels and by replacing the clutch described by any other device having the same object.

I claim:

1. In a stop motion for core wrapping machines, a rotatable spindle, means supporting said spindle, part of said spindle being enlarged, a quick screw thread carried by the enlarged part of said spindle, a ring mounted on said spindle, said ring being movable longitudinally of said spindle, means carried by the ring engaging said screw thread, said ring normally rotating with said spindle, lateral arms carried by said ring, a vertical oscillatory lever, means retaining said lever oscillated in one position, a spring for oscillating said lever in the other position and means causing said ring to traverse the spindle longitudinally to stop the machine in the absence of material for winding. 5 10 15

2. In a stop motion for core wrapping machines, a rotatable spindle, means supporting said spindle, part of said spindle being enlarged, a quick screw thread carried by the enlarged part of said spindle, a ring mounted on said spindle, said ring being movable longitudinally of said spindle, means fixed with the ring engaging said screw thread, said ring normally rotating with the spindle, lateral arms carried by said ring, said arms being in equilibrium, means for 20 25 30 driving said spindle, a vertical oscillating clutch lever arm, means for retaining said arm in one oscillated position, and a spring for return movement of said arm, the ring descending along the screw thread upon the absence of driving material.

ARMAND BÈS.
